PALLET ENCLOSURE

David Rawle, Berwyn, Pa., assignor to Clinch-Tite Corporation, Berwyn, Pa., a corporation of Delaware
Filed Feb. 18, 1965, Ser. No. 433,738
5 Claims. (Cl. 217—65)

This application is a continuation-in-part of my application Serial Number 357,636, filed April 6, 1964, and now abandoned.

This invention relates to enclosures for materials handling pallets, and provides an improved enclosure having a locked and optionally sealed corner structure in which the enclosure walls are operable to transmit to the corners either outward or inward forces in such a manner that the lock and seal are reinforced in proportion to the amount of force so transmitted. In addition, the invention provides an improved device for connecting a removable wall to the adjacent walls of a pallet enclosure.

The requirements of enclosed palletized materials handling vary, enclosures sometimes being used to provide protection to the contents against external forces, other times to segregate and confine loose bulk-handled material. Obviously, as the uses vary, so do the requirements for an effective enclosure. Very often, tightly sealed corners are required, with the seal being resistant to development of leaks during use. At the same time, it is highly desirable that the enclosure be easily disassembled when not in use, to facilitate its storage or return to the point of origin. The enclosure must exhibit strength in various respects; in some cases the main concern is resistance to external pressure, in other cases to internal pressure. Other important factors are versatility, interchangeability of individual wall sections, and the ability to remove an individual wall to gain access to the contents without having to disassemble the entire enclosure even when there is little maneuvering room in front of the wall being removed. Finally, all of the above requirements must be met while keeping the simplicity of design and materials at a maximum and the cost at a minimum.

The greatest difficulty exists when sealed corners are required. High pressure from the enclosed contents or a sharp blow from the outside can often create leaks in the corners.

It is thus a particular object of this invention to provide a pallet enclosure with corners locked against inward or outward hinging, said lock being independent of the incorporation of a given corner into a complete enclosure.

A further object of the invention is to provide a pallet enclosure with sealed corners so structured that the force of external or internal pressure is caused to reinforce, rather than break, the corner seals.

A still further object of the invention is to provide such a pallet enclosure assembled from individual wall sections, with the individual walls capable of being removed in tight quarters without disturbing the rest of the enclosure.

A further object is to provide improved means for fastening together adjacent walls in a pallet enclosure having removable walls.

A still further object of the invention is to provide such a pallet enclosure constructed entirely from wood and simple and inexpensive connecting elements.

Further objects and advantages of the invention will become apparent from its detailed description below.

The objects are realized through the application of an advantageous principle of corner construction and assembly. The four-walled enclosure of the invention comprises four individual, preferably wooden, wall structures, removably hinge-connected to form a single enclosure unit.

The hinge connecting is accomplished by means of

2

connecting elements, advantageously hooks and eyes formed by appropriately bent but rigid in use, metal rods, e.g. of $\frac{3}{8}$ or $\frac{1}{2}$ inch thickness, installed near the vertical edges of the walls in such a manner that the walls can be joined together, in one embodiment, by means of relative vertical movement, the connecting elements bringing adjacent walls together at the corners in tight end-to-face abutment. In another embodiment, a rotatable connecting element is employed to avoid the necessity of relative vertical movement of walls. Importantly, in all embodiments the connecting elements provide a vertical hinging axis so located that the area of end-to-face abutment is spaced in either an inward or outward sense from said axis. The hinging axis is rigidly defined, in that its horizontal position is substantially rigidly fixed relative to the two adjacent walls. Although the terms hinge-connected and hinging axis are employed herein, they should not be taken to mean that the walls of the enclosure are freely hinged with respect to each other, since in fact all corners of the invention are locked against hinging in at least one direction, with one embodiment having corners locked against hinging in both directions. Rather, the hinging terminology is intended to reflect the fact the walls are joined to define an axis about which moments are produced by attempting to rotate adjacent walls against the corner locking of the invention.

In addition to corner locking, the invention provides an optional continuously sealed corner feature with both the lock and the seal being reinforced in response to internal or external pressure, depending upon the sense (i.e. inward or outward) of the spacing between the hinging axis and the end-to-face abutment. For example, to reinforce against internal pressure, the abutment is spaced outwardly of the hinging axis; outward pressure against the abutting walls produces turning moments about the corner axis causing the abutting surfaces of the walls to press tighter against each other, thereby preventing substantial outward hinging motion and reinforcing the lock or seal. The reinforcement occurring at a given corner is wholly independent of the other walls of the enclosure. Furthermore, when the four walls are incorporated into a single enclosure unit, the walls are additionally restrained against hinging motion in both the inward and outward senses, thus providing a completely stable enclosure without the use of bands, wires, slats or other reinforcing materials. All that remains is to secure the enclosure to the pallet base and add a cover if such is desired. Depending upon the nature of the cargo, either internally or externally hinged wall structures may be chosen for installation on a standard pallet base.

In the drawings,

FIG. 1 is a perspective view of an externally hinged embodiment;

FIG. 2 is a horizontal cross-section of one corner taken through a hook and eye assembly;

FIG. 3 is a vertical section taken through line 3—3, FIG. 2;

FIG. 4 is a broken away perspective view showing walls being brought together to form a corner;

FIG. 5 is a perspective view of an internally hinged embodiment;

FIG. 6 is a horizontal cross-section of one corner taken through a hook and eye assembly;

FIG. 7 is a vertical section taken through line 7—7 of FIG. 6;

FIG. 8 is a horizontal section of one corner of a third embodiment, taken through a hook and eye assembly;

FIG. 9 is a vertical cross-section taken through line 9—9 of FIG. 8;

FIG. 10 is a perspective view of the third embodiment; FIG. 11 is a perspective view showing walls of the third

embodiment being brought together to form a corner; FIG. 12 is a horizontal cross-section through the corner of a variation of the third embodiment;

FIG. 13 is a perspective view of an externally hinged embodiment employing a rotatable eye member; and

FIG. 14 is a side view of one corner of another embodiment having a rotatable hook member.

Referring to the drawings, a typical wall structure 12 employed in the enclosure of the invention comprises a series of horizontal cleats 14 and a continuous wall panel 16, the cleats attached to the panel, usually but not necessarily externally, and strengthening it. Normally, the cleats 14 and panel 16 will be coterminous to provide smooth vertical ends 19 on the wall structures.

Considering first the externally hinged embodiment of FIGS. 1-4, each eye element 25 and hook element 26 has a rigid supporting shaft 27 sandwiched between the cleats and the panel, with the hook and eye protruding from the end 19 of the wall structure 12. A right angled groove in the inner surface of the cleat provides shaft passage 28, in which is housed the shaft 27 having a similarly right angled form, thereby firmly anchoring it in the wall structure. It will be appreciated that the entire rigid-in-use hook and eye elements of the locked and sealed corners can be formed from originally straight metal rods to provide a very durable yet inexpensive construction.

In order to provide the desired end-to-face abutment when the walls are connected together, the distance between the center of the eye 25 and the end 19 of the eye-bearing wall structure is equal to the distance between the center of the hook and the face 20 of the hook-bearing wall structure, this common distance being denoted as X in FIG. 2.

In connection with this limitation it is of utmost importance that any manufacturing tolerances keep the distance between the end and the axis of its connecting member smaller rather than larger than the distance between the face and the axis of its connecting member. Thus, when the wall structures extend at right angles to each other, end-to-face contact is always insured and in the case of slight dissimilarity in the two distances, the wood will resiliently deform under pressure to achieve the lock and seal.

As best shown in FIG. 4, each pair of adjacent walls are assembled, preferably by means of relative vertical movement, and define a vertically elongated end-to-face abutment area 31, as well as a vertical hinging axis 30 passing through the center of the hook and eye. According to the invention, in the externally hinged embodiment, the hinging axis 30 is spaced outwardly from the abutment area 31. Since the abutment in this embodiment is made up wholly of abutment between adjacent continuous panels 16, both a lock and continuous seal are provided at the same time. Any application of inward forces to an assembled corner serves to reinforce the seal at that corner, and at the same time the walls are locked against substantial inward hinging. This embodiment of the invention is particularly useful when there is a danger that external pressure against the enclosure will break the corner seal. Furthermore, the external location of the connecting elements enables faces 20 to form a completely smooth interior, well adapted to carry granular or semi-liquid substances without interference with the irregular or creviced elements of the enclosure.

It will be noted that since in the particular construction of panels 16 and cleats 14 shown, abutment seal 31 consists exclusively of end-to-face abutment of the panels 16, the character of the seal can be controlled simply by control of the panel substance. Of course, the hooks and eyes can be interchanged from the positions shown, and the direction of the hook can be either up or down, except that they should be arranged so that at least one wall can be removed from the assembled enclosure by a simple upward movement.

The internally hinged embodiment of the invention is shown in FIGS. 5-7, and employs the same corner locking principle as does the externally hinged embodiment. In this case, however, the hinging axis 30a is spaced in an inward sense from the end-to-face abutment 31a, the abutment thus locking the walls against outward hinging.

Again, the angled shafts 27a of the hook and eye elements are sandwiched in grooves 28a in the cleats. In this embodiment, however, the hooks 26a and eyes 25a protrude from holes 17a in panels 16a into the interior of the enclosure.

Once again the distance X (FIG. 6), measured between the center of the hook to face 20a of the hook-bearing wall structure, and from the center of the eye 15 to the end 19a of the eye-bearing wall structure is critical to proper end-to-face abutment of the assembled walls. Of course, the distance X is here measured inwardly from face 20a, rather than outwardly as before.

Another feature of the internally hinged embodiment 20 is the fact the cleats 14a abut panels 16a supplementing the abutment between adjacent panels 16a to give a much wider abutment 31a at the cleats, which is useful in some applications, the wide abutment greatly increasing the strength of the corners and their locked resistance to 25 outward hinging. While the above-mentioned abutments between adjacent panels 16a as well as panels 16a and cleats 14a provide locked corners, only the panel-to-panel abutment extends continuously along the entire length of the corners. This panel-to-panel abutment is 30 generally not sufficient to give tightly sealed corners, due to a secondary hinging axis set up at the outer edge of the cleat-to-panel abutment. In order to provide tightly and continuously sealed corners in this embodiment, it is necessary simply to add vertical cleats 15a along the 35 lengths of the appropriate outer vertical edge of each wall, as shown at the corners in FIG. 5. The abutment of cleat 15a to face 20a of the adjacent wall is then reinforced in response to attempted outward hinging, on the same principle as described earlier. In this manner, 40 cleat-to-panel abutment is provided along the entire vertical extent of the corners, giving a tight seal.

The embodiments described thus far employ the unique corner reinforcing principle of the invention to prevent hinging in only one sense, either inward or outward. 45 In order to have corner locking and seal reinforcement in a single enclosure in response to hinging attempts in both the inward and outward senses, it is necessary to have the portions of abutment area spaced both inwardly and outwardly from the hinging axis. A simple way 50 to accomplish this, shown in FIGS. 8-11, is to split the abutment 31b with recesses 32b in one of the walls, the connecting elements 26b on that wall being mounted in said recesses. The recess will advantageously be in the face 20b of the wall and will be tall enough to allow 55 vertical movement of the non-recessed connecting element sufficient to permit hooking and unhooking of said elements. The non-recessed element will protrude from the end 19b of the adjacent panel.

In order to allow assembly and disassembly of this 60 embodiment, horizontal slots 40b are provided in the cleats in which the recesses 32b are cut, slots 40b communicating with the recesses. The eyes 25b are then passed through slots 40b in order to enter or leave the recesses. In assembling this embodiment, three corners 65 are assembled in the usual manner, without necessarily employing slots 40b. The fourth panel will have its eyes, except for the top eye, inserted through the slots on one side by relative horizontal movement. Relative vertical movement will then interlock the connecting elements.

By adding vertical cleats 15b as shown in FIG. 10 along the outer vertical edges of the walls, an outwardly spaced abutment seal is provided along the entire vertical extent of the corner. Vertical cleats 15b can be segmented and inserted between horizontal cleats 14b, or

the horizontal cleats can be shortened to allow continuous vertical cleats.

While only one wall per corner need be vertically cleated to provide a fully sealed corner, the use of a second continuous vertical cleat to house recess 32 is highly desirable, giving additional strength.

Naturally, the recessing can be replaced with parallel slats 33b, shown in FIG. 12, as will be well understood by those skilled in the art.

In all embodiments the spacing between hinging axis and abutment seals can be varied in degree as well as sense, a variation in degree affecting the leverage about the axis, and, therefore, the quality of the seal reinforcement.

A remarkable feature of the invention is that a variety of advantageous corner assemblies can be obtained by simply controlling the sense and degree of spacing between the abutment seals and the hinging axis, yet all at a minimum of cost. In no case is it necessary to use more than the simplest of wooden constructions, with a few metal hooks and eyes. In comparison, the prior art has employed expensive and elaborate structures, often of metal, without providing the advantages disclosed herein.

When not in use, the individual walls are easily stacked out of the way. Furthermore, it is possible, during transit, to remove an individual wall without disrupting the entire enclosure. In any of the embodiments the walls are easily assembled together and then attached in well known ways to a standard pallet base. A cover may be added when desired.

An improved form of connecting element, particularly useful in the locked corner enclosures of the invention, is shown in FIGS. 13-14. In the externally hinged embodiment of FIG. 13 vertical cleats 15c are employed on the exterior of panel 16c, with one such cleat located at each vertical edge of the wall. Each rotatable connecting element 42 is sandwiched between cleat 15c and panel 16c, with shaft portion 44 elongated and extending all the way across cleat 15c, to allow the desired rotation. At one end of shaft 44 is an interlocking portion in the form of eye 43, the shaft being bent at the other end to form handle 45. Handle 45 and eye 43 lie in a common plane. A recess 50 is cut in cleat 15c, allowing the shaft 44 to be slid away from the adjacent wall in order to retract eye 43 behind end surface 19c of the wall structure, as shown at the middle and lower hook and eye connections of FIG. 13. Hook member 41 is located at the end of the next adjacent wall structure in the same manner as the embodiment of FIG. 1, except that the hook 47 must be sufficiently short to allow the eye to interlock with it by passing fully over it in a rotational movement through 180°. Each wall structure in the enclosure has rotatable eye members along one end and hook members along the other end. The recesses 50 can be eliminated, if desired, leaving rotatable but non-retractable eye members.

In operation, the wall structures are assembled into an enclosure by simply retracting all the rotatable members 42 behind edge 19c, placing two panels together in end-to-face abutment, and locking in turn each pair of connecting elements by raising handle 45 to its uppermost position (see the lower connection of FIG. 13), sliding it toward the adjacent wall until the eye 43 is positioned behind hook 47, then rotating the handle downwardly through 180°, the eye passing fully over hook 47 and encircling, in its locked position, shaft portion 49. Rubber band 51, encircling cleat 15c, in groove 51', is then slipped over handle 45 to secure member 42 in place.

The system just described is highly advantageous in enabling installation or removal of a single wall, e.g., while in transit. Once the connecting elements are unlocked, the physical placement or withdrawal of the wall structure can be accomplished by exclusive lateral slid-

ing of the wall relative to the rest of the enclosure, as indicated by the arrows on the walls of FIG. 13. No threading of connecting elements, while simultaneously moving the wall, is required.

5 In the embodiment of FIG. 14 a rotatable hook member 42d replaces the member 42 of FIG. 13. Member 42d is identical to member 42 except that, instead of an eye 43, a hook 52 extends from one end of shaft 44d as the interlocking portion, at right angles to handle 45d at the other end of the shaft. Member 42d is installed in the wall structure in the same manner as member 42. The left hand end of the adjacent wall structure contains a slot 53 to receive hook 52. In the embodiment shown, slot 53 is formed by sandwiching a bent rod 54 between cleat 15d and panel 16d, leaving a loop 55 extending out from wall surface 19d. Optionally, other types of slots may be employed, including slots formed wholly in the wooden wall structure.

20 In operation, to lock hook member 42d into slot 53, after adjacent panels are placed in end-to-face abutment, handle 45d is rotated into a horizontal plane, bringing hook 52 into a vertical plane. By sliding the handle toward the adjacent wall the hook will pass into loop 55. Then the handle is simply lowered, locking hook 52 into loop 55 (FIG. 15), and the rubber band is slipped into place.

25 The detailed description given above is intended to be suggestive of the many possible embodiments of the invention, and various changes in the specific details will be obvious in view of the spirit and scope of the invention.

30 What is claimed is:

1. In a pallet enclosure, a corner construction comprising a wall end and a wall face defined by adjacent first and second wall structures, said wall structures having respective connecting means adapted to interlock to bring said end and face into abutment and to rigidly define a hinging axis spaced in at least one predetermined sense from at least a portion of said end-to-face abutment, said axis and said end-to-face abutment cooperating to lock said wall structures against hinging motion in the sense opposite to said predetermined sense, one of said connecting means comprising a rotatable member having a supporting shaft journaled in said wall structure and a locking portion at one end of said shaft, adapted to interlock with a corresponding locking portion of the other of said connecting means, said rotatable member being adapted to be rotated about said shaft between a locked position in which said locking portion of said rotatable member is interlocked with said corresponding locking portion and an unlocked position in which said locking portion can be removed from said corresponding locking portion.

55 2. The construction of claim 1 wherein said shaft is slidable along its axis of rotation to move said rotatable member between an extended position in which said locking portion of said rotatable member extends beyond the end of its wall structure and a retracted position in which said locking portion is retracted behind said wall end.

60 3. The construction of claim 1 wherein said locking portion of said rotatable member comprises an eye, and said connecting means on said adjacent wall comprises a vertically extending hook, said eye oriented relative to said shaft so that the eye lies in a vertical plane when said rotatable member is in its locked position.

65 4. The construction of claim 1 wherein said locking portion of said rotatable member comprises a hook and said connecting means on said adjacent wall comprises a slot adapted to receive said hook.

70 5. A pallet enclosure having multiple wall structures wherein said wall structures are constructed and arranged so that all but the last of said wall structures can be locked together in a self-supporting structure during

assembly, and respective connecting means are disposed near the opposite vertical edges of the last wall structure and near the remaining free vertical edges of said assembled wall structures, said connecting means on said last wall structure adapted to cooperate with the connecting means on said assembled wall structures to enable said last wall structure to be assembled into said enclosure by means of exclusive lateral sliding of said last wall relative to the rest of said enclosure, said cooperating connecting means including a rotatable member having a supporting shaft and a locking portion at one end of said shaft, said rotatable member being adapted to be rotated about said shaft between a locked position in which said locking portion is engaged with a corresponding locking portion of said connecting means on the adjacent wall structure, and an unlocked position in which said locking portion of said rotatable member can be removed from said corresponding locking portion, said last wall being adapted to be locked into said en-

closure by rotating said rotatable member from said unlocked position into said locked position after the completion of said lateral sliding.
